SHEET HANDLING APPARATUS

Andrew Neuhart, West View, Pa., assignor to
 Miller Printing Machinery Co., Pittsburgh, Pa.,
 a corporation of Pennsylvania

Application August 15, 1941, Serial No. 406,975

7 Claims. (Cl. 271—54)

This invention relates to sheet handling apparatus and particularly to sheet handling apparatus wherein sheets are handled and advanced from point to point by suckers. The invention further relates to sheet handling apparatus employing a movable carrier having suckers thereon for advancing sheets upon movement of the carrier and means for controlling operation of the suckers.

While the invention is of general application in the handling of sheets it has particular utility when embodied in a sheet feeder for taking sheets from a pile and advancing them sequentially to a printing cylinder or other means for operating upon the sheets one by one. When employing the invention in a feeder I provide separating or lifting suckers which are movable in a generally vertical direction for lifting sheets one by one from the top of a pile, the lifting suckers delivering sheets to a carrier having transfer suckers thereon for advancing the sheets toward the cylinder. I prefer to employ a pair of cooperating carriers each having sheet advancing suckers thereon and operating in such manner that the suckers of one of the carriers advance a sheet from the lifting suckers to an intermediate point where the sheet is transferred to the suckers of the second carrier to be further advanced or transferred to the drop guides of the cylinder. The general structure and mode of operation of the feeder may be as described and claimed in copending application Serial No. 319,862.

The present trend, as those skilled in the art appreciate, is toward higher and higher speeds. In modern high speed printing presses sheets are handled and printed at the rate of several thousand per hour. This requires accurate and positive handling of the sheets. Indeed in presses of some types the speed and accuracy of the sheet handling equipment are the factors which limit the speed of the press as a whole. It is especially important when sheets are handled by suckers that the operation of the suckers, and particularly the supplying and cutting off of suction, is performed with great accuracy relatively to the position of the sheets when the suction is admitted to the suckers and when the suction is cut off from the suckers.

I have found that improved results can be obtained in speed and accuracy of sheet handling by the use of movable suckers by employing a valve intermediate the sucker and the source of suction for controlling admission of suction to the sucker together with means movable synchronously with the sucker for operating the

valve and resilient means maintaining the valve in at least one of open and closed positions. Under certain circumstances I find it highly desirable to employ a snap action valve operated by a spring and having means maintaining the valve in open or closed position against the action of the spring and means for allowing the spring to snap the valve closed or open at a predetermined time in the cycle of operations so as to 5 shut off or admit the suction very rapidly to release or take the sheet. I also have found that by positioning the valve for operating a lifting sucker adjacent the sucker rather than at a point considerably removed from the sucker at the lower portion of the apparatus and with a very short connecting tube between the valve and the sucker more accurate results can be obtained in operation of the lifting sucker and release of sheets thereby at precisely the proper moment. 10 I also have found that when the invention is embodied in a feeder for registering sheets to guide means such as cylinder drop guides superior results are accomplished by providing a valve on an oscillatable carrier which advances sheets by suction, the valve being disposed intermediate suckers on the carrier and the source of suction for controlling the admission of suction to the suckers, and means for progressively closing the valve as a sheet carried by the suckers approaches the guide means. This insures accurate control of the sheet while allowing it to move relatively 15 to the suckers upon engagement with the guide means.

Other details, objects and advantages of the invention will become apparent as the following description of a present preferred embodiment thereof proceeds.

In the accompanying drawings I have shown a 20 present preferred embodiment of the invention, in which

Figure 1 is a plan view of a portion of a sheet feeder;

Figure 2 is an elevational view of a portion of 25 the feeder shown in Figure 1;

Figure 3 is a fragmentary plan view of a sucker operating valve and the operating mechanism therefor;

Figure 4 is a fragmentary elevational view of 30 the structure shown in Figure 3;

Figure 5 is an enlarged plan view of a portion 35 of the structure shown in Figure 3;

Figure 6 is a fragmentary plan view of another 40 sucker operating valve and the operating mechanism therefor;

Figure 7 is a fragmentary elevational view of the structure shown in Figure 6;

Figure 8 is an enlarged elevational view of a portion of the structure shown in Figure 7;

Figure 9 is a fragmentary elevational view of a lifting sucker operating valve and the operating mechanism therefor;

Figure 10 is a horizontal cross-sectional view through the structure shown in Figure 9;

Figure 11 is an elevational view of a portion of the structure shown in Figure 9 as viewed from the right-hand side of that figure; and

Figure 12 is an enlarged horizontal cross-sectional view taken on the line XII—XII of Figure 11.

Referring now more particularly to the drawings, Figures 1 and 2 show portions of a sheet feeder for feeding sheets sequentially to a printing or like cylinder. Portions of the feeder structure not related to the present invention are omitted. The cylinder is designated by reference numeral 2. It is provided with the usual drop guides 3. Sheets are advanced from right to left viewing Figures 1 and 2 toward the drop guides 3 upon a feed board 4. The sheets are handled throughout by suckers each connected with a source of suction and means are provided for operating the suckers as will be explained in detail below.

A pile of sheets to be fed to the drop guides is shown at 5. The sheets are taken from the top of the pile one by one by separating or lifting suckers 6 which partake of controlled generally vertical oscillatory movement. Each of the suckers 6 is carried by a head 11'. The heads 11' are in turn carried by a transverse pipe 11. A pair of opposed generally vertically extending and oscillating operating rods 7 are connected at their upper ends with the pipe 11 and impart generally vertical oscillatory movement to such pipe and hence to the suckers 6 carried thereby in timed relation with the other elements of the feeder as well known in the art. A source of suction, as, for example, a vacuum pump (not shown), is provided at a suitable location. A tube 8 is connected with the pump and with a valve 9. Another tube 10 extends from the valve 9 to the pipe 11. A tube 12 extends from the pipe 11 to each of the suckers 6. A coil spring 12' is positioned about the rod 13' of each of the suckers 6 and bears between the lower surface of the corresponding head 11' and the upper surface of a collar 14' fixed to the rod 13'. The mounting and oscillatory movement of the suckers may be effected in known manner and the present invention does not reside therein.

Mounted in the feeder frame is a transversely extending shaft 13 which partakes of oscillatory motion. The shaft 13 may be driven by any suitable driving means. Fixed to the shaft 13 are two pinions 14 and 15, respectively. The pinion 14 meshes with a rack 16 and the pinion 15 meshes with a rack 17. The rack 17 forms a part of an upper oscillatable carrier and the rack 16 forms a part of a lower oscillatable carrier. The upper and lower carriers always move in opposite directions. The upper carrier carries a pair of suckers 18 and the lower carrier carries four suckers 19. When the upper carrier is in its extreme right-hand position the suckers 18 thereof take a sheet from the lifting suckers 6. When the upper carrier moves toward the left such sheet is carried down over the feed board 4. When the upper carrier reaches the left-hand end of its stroke the lower carrier is at the right-

hand end of its stroke and the sheet is transferred from the suckers 18 to the suckers 19. Then the lower carrier moves toward the left and registers the sheet to the drop guides 3. 5 Such a feeder is disclosed in said copending application Serial No. 319,862.

The present invention is concerned primarily with the suction valves and their control and operation. Mention has been made above of 10 the valve 9 for controlling the suction to the suckers 6. Mounted on the upper carrier and movable therewith is a valve 20 for controlling the suckers 18. Mounted on the lower carrier and movable therewith is a valve 21 for controlling the suckers 19. The valves 21, 20 and 9 and their operating means will now be described in detail.

The valve 21 has a connection 22 to the vacuum pump and a connection 23 to a transverse pipe 24 carrying the suckers 19. Tubes 25 connect the interior of the pipe 24 with the suckers 19. The valve 21 has a slideable valve element 26 carried by a valve stem 27. The valve is urged toward open position by a coil spring 28. 25 The valve stem 27 has a transverse slot 29 into which an arm 30 of a lever 31 pivoted at 32 to an arm 32' carried by the valve casing is adapted to extend. The lever 31 has a second arm 33 extending substantially at right angles to the arm 30. The arm 30 of the lever 31 is urged to turn in the counter-clockwise direction about the axis of the pivot 32, viewing Figure 4, by a spring 34. 30 Mounted in the feeder frame is an abutment member 35 for operating the lever 31, as will presently be described. Adjustably mounted on the feeder frame is a cam 36 adapted to cooperate with a roller 37 carried by the valve stem 27, as will presently be described. The cam 36 has two operative portions 38 and 39, as shown 35 in Figure 3. It is adjustably fastened to the feeder frame by screws 40 passing through elongated slots 41 in the cam, also shown in Figure 3.

The suckers 19 are for registering sheets to the drop guides 3. When the lower carrier which 40 carries the suckers 19 is moving toward the right, viewing Figures 2 and 3, the valve 21 is closed, as shown in Figures 3, 4 and 5. It is maintained closed by the arm 30 of the lever 31 as such arm enters the slot 29 in the valve stem. As the lower 45 carrier approaches the right-hand extremity of its travel the arm 33 engages the abutment member 35. This causes the lever 31 to turn through a small angle in the clockwise direction about the axis of the pivot 32, viewing Figure 4, until the arm 30 rises out of the slot 29. As soon as the arm 30 leaves the slot 29 the spring 23 snaps the valve open so that suction is admitted to the suckers 19. The abutment member 35 is arranged on the frame so that it operates the valve 21 substantially at the instant when the lower carrier is at the right-hand extremity of its movement. At the same instant the upper carrier is at the left-hand extremity of its movement. The admission of suction to the suckers 19 causes such suckers to take from the suckers 18 a sheet which the suckers 18 have carried down the feed board. Then when the lower carrier moves toward the left, viewing Figures 1 and 2, the suckers 19 carry the sheet toward the drop guides 3.

As the front edge of the sheet approaches the drop guides 3 the roller 37 on the valve stem 27 engages the first operative portion 38 of the cam 36. This pushes the valve stem 27 downwardly, viewing Figure 3, sufficiently to partially, but not

entirely, shut off the vacuum to the suckers 18. As movement of the lower carrier continues toward the left, viewing Figures 1 and 2, the front edge of the sheet engages the drop guides 3. Since the suction admitted to the suckers 18 has been reduced by operation of the operative portion 38 of the cam 36 upon the valve stem, when the front edge of a sheet strikes the drop guides 3 the suckers 18 will continue to move toward the left, viewing Figures 1 and 2, for a short distance, this movement, due to the decreased but nevertheless continuing suction in the suckers 18, resulting in gently urging the sheet against the drop guides, the suckers moving forward relatively to the sheet while the sheet is engaged and held stationary by the drop guides. Substantially at the instant when the lower carrier is at the left-hand end of its stroke, viewing Figures 1 and 2, the operative portion 39 of the cam 36 operates upon the roller 31 to entirely close the valve 21 and thus shut off suction from the suckers 18. But at the instant the valve stem is pushed down to the position shown in Figures 3, 4 and 5, when the valve is fully closed, the spring 34 causes the arm 30 of the lever 31 to enter the slot 29 and thus latch the valve in closed position. The lower carrier and the valve 21 are thus ready for commencement of another cycle of operations as above explained.

Referring now to the valve 20 for controlling the suckers 18, such valve has a connection 42 to the vacuum pump and a connection 43 to a transverse pipe 44 carrying the suckers 18. Tubes 45 connect the interior of the pipe 44 with the suckers 18. The valve 20 has a slideable valve element 46 carried by a valve stem 47. The valve 20 is shown in open position in Figures 6, 7 and 8. Fastened to the valve stem 47 by a screw 48 is a plate 49. Fastened to the valve casing by a screw 50 is a spring 51 having a V-shaped extremity 52. When the valve is open the extremity 52 of the spring 51 lies to the right of the plate 49, as shown in full lines in Figure 8. When the valve is closed the extremity 52 of the spring 51 lies to the left of the plate 49, as indicated in chain lines in Figure 8. Movement of the valve stem toward the right is limited by an enlargement 53 at its left-hand end viewing Figure 8. Thus the spring 51 resiliently maintains the valve in both open position and closed position.

The valve element 46 is moved between open and closed positions by valve operating members 54 and 55. The feeder frame carries a pair of brackets 56 one of which carries a casing 57 receiving the valve operating member 54 and the other of which carries a casing 58 receiving the valve operating member 55. A spring 59 in the casing 57 urges the valve operating member 54 toward the right, viewing Figures 6 and 7, and a spring 60 in the casing 58 urges the valve operating member 55 toward the left, viewing Figures 6 and 7. When the upper carrier moves toward the right, viewing Figures 1 and 2, and also viewing Figures 6 and 7, the right-hand end of the valve stem engages the valve operating member 55 which moves the valve from closed to open position. Conversely, when the carrier moves toward the left the left-hand end of the valve stem engages the valve operating member 54 which moves the valve from open to closed position. Movement of the valve from one to the other of open and closed positions causes the plate 49 to temporarily displace upwardly the V-shaped extremity 52 of the spring 51 and at the conclusion of the movement the spring moves

downwardly to resiliently maintain the valve in the desired position.

The springs 59 and 60 serve a twofold function. They cushion the shock of the valve against the valve operating members 54 and 55, respectively, and they also provide for proper operation of the valve at various speeds of operation of the feeder. When the feeder operates at relatively high speed the carriers have somewhat greater linear travel due to inertia. If the valve operating members 54 and 55 were stationarily mounted there would be danger of damage to the parts upon speeding up of the feeder. The springs 59 and 60 yield sufficiently when the valve strikes the members 54 and 55 that such members move slightly with the valve when the feeder is operating at high speed. The springs 59 and 60 are stiff enough to insure operation of the valve at any speed. The resistance to operation of the valve offered by the spring 51 and friction of the parts is less than the strength of each of the springs 59 and 60.

As the upper carrier moves toward the right, viewing Figures 1 and 2, the valve 20 is closed. As the carrier reaches the right-hand extremity of its movement the valve operating member 55 opens the valve 20 to admit suction to the suckers 18 to enable them to take a sheet from the suckers 6. As the carrier moves toward the left the sheet is carried with it and as it reaches its left-hand extremity the valve 20 is closed by the valve operating member 54, thus cutting off suction to the suckers 18 at the instant suction is admitted to the suckers 18 whereby the sheet is transferred from the former to the latter. The upper carrier then moves toward the right with the valve 20 closed and the cycle of operations is repeated.

The valve 9 has, as above stated, a connection 8 to the vacuum pump and a connection 10 to the lifting suckers 6. The valve has a slideable valve element 61 shown in closed position in Figures 9 to 12, inclusive. The structure of the valve 9 is similar to that of the valve 21, a spring 62, however, urging the valve 9 toward closed position rather than toward open position. A lever 63 is pivoted at 64 to a plate 65 which is in effect unitary with the valve casing, which in turn is carried by the feeder side frame by a bracket 66. The lever 63 carries a detent 67 adapted to enter a slot 68 in the valve stem. The lever 63 is urged downwardly or toward the position in which the detent 67 will enter the slot 68 by a spring 69. A generally vertically oscillatable operating rod 70 carries a collar 71 having a roller cam 72 adapted upon downward movement of the rod 70 to engage the head 73 of the valve stem to move the valve to open position.

When the suckers 6 move down to take a sheet from the top of the pile 5 the valve 9 is closed, as shown in Figures 9, 10, 11 and 12. Just as the suckers 6 come to the lower extremity of their generally vertical travel the rod 70, which is also moving downwardly, brings the cam 72 into engagement with the head 73 of the valve stem to push the valve stem toward the left, viewing Figure 11, to open position. When the valve stem is pushed toward the left, viewing Figure 11, the detent 67 drops into the slot 68 and holds the valve open. Thus the suckers 6 are caused to take the top sheet from the pile of sheets 5 and separate it from the sheets below in readiness for raising it in a feeding movement.

While the suckers 6 rise carrying a sheet the valve 9 is open. Just as such suckers reach the upper extremity of their movement the cam 72

on the rod 70 strikes the lever 63 and raises the same so that the detent 67 is raised out of the slot 68 whereupon the spring 62 snaps the valve closed. This is done just at the moment the suckers 18 take the sheet from the suckers 6. The suckers 6 then move downwardly with the valve 9 closed and the cycle is repeated.

The structure above described results in particularly precise and accurate handling and registry of sheets and is especially adaptable for high speed operation. I find that by means of the valves and control mechanism which I employ I can handle sheets at a much faster rate than heretofore. The sheets are properly presented to the drop guides of the feeder without having their leading edges torn or nicked and without bouncing back. The sheets are properly and accurately transferred from the lifting suckers to the suckers on the upper carrier and from the suckers on the upper carrier to those on the lower carrier.

While I have shown and described a present preferred embodiment of the invention it is to be distinctly understood that the invention is not limited thereto but may be otherwise variously embodied within the scope of the following claims.

I claim:

1. Sheet handling apparatus comprising an oscillatable carrier, a sucker thereon, a source of suction, a valve on the carrier intermediate the sucker and the source of suction for controlling admission of suction to the sucker and yieldable abutment means relatively to which the carrier moves adapted to engage the valve upon oscillation of the carrier to operate the valve.

2. Sheet handling apparatus comprising a movable sucker, a source of suction, a valve intermediate the sucker and the source of suction for controlling admission of suction to the sucker, spring means urging the valve to one of open and closed positions, latch means for holding the valve in the other position against the action of the spring means, means operable upon movement of the sucker in one direction for rendering the latch means inoperative to permit the spring means to move the valve to the first mentioned position and means operable upon movement of the sucker in the opposite direction for moving the valve against the action of the spring means to the second mentioned position and rendering the latch means operative to hold it there.

3. Sheet handling apparatus comprising an oscillatable carrier, a sucker on the carrier, a source of suction, a valve on the carrier intermediate the sucker and the source of suction for controlling admission of suction to the sucker, spring means urging the valve to one of open and closed positions, latch means for holding the valve in the other position against the action of

the spring means, means operable upon movement of the carrier in one direction for rendering the latch means inoperative to permit the spring means to move the valve to the first mentioned position and means operable upon movement of the carrier in the opposite direction for moving the valve against the action of the spring means to the second mentioned position and rendering the latch means operative to hold it there.

4. Sheet handling apparatus comprising an oscillatable carrier, a sucker on the carrier, a source of suction, a valve on the carrier intermediate the sucker and the source of suction for controlling admission of suction to the sucker, spring means maintaining the valve resiliently in at least one of open and closed positions, means operable upon movement of the carrier in one direction for moving the valve to one of said positions and means operable upon movement of the carrier in the opposite direction for moving the valve to the other of said positions.

5. Sheet feeding apparatus comprising a carrier, a sheet advancing sucker on the carrier, guide means to which sheets advanced by said sucker are adapted to be registered, a source of suction, a valve on the carrier intermediate the sucker and the source of suction for controlling the admission of suction to the sucker and valve operating means comprising a follower on the valve and a multiple step cam positioned to be engaged by said follower for progressively closing the valve as a sheet carried by the sucker approaches said guide means.

6. Sheet feeding apparatus comprising a carrier, a sheet advancing sucker on the carrier, guide means to which sheets advanced by said sucker are adapted to be registered, a source of suction, a valve on the carrier intermediate the sucker and the source of suction for controlling the admission of suction to the sucker, spring means for urging the valve toward open position to admit suction to the sucker, latch means for holding the valve in closed position against the action of said spring means, trip means operative upon movement of the carrier generally away from said guide means to render the latch means inoperative to permit the spring means to open the valve and cam means relative to which the carrier moves for progressively closing the valve against the action of the spring means as a sheet carried by the sucker approaches said guide means.

7. Sheet handling apparatus comprising a sucker, a source of suction, an oscillatable valve intermediate the sucker and the source of suction for controlling admission of suction to the sucker and resiliently yieldable abutment means separate from the valve and relatively to which the valve oscillates for operating the valve.

ANDREW NEUHART.
